UNITED STATES PATENT OFFICE.

WALDEMAR BERGER, OF HÖCHST-ON-THE-MAIN, GERMANY, ASSIGNOR TO FARBWERKE VORM. MEISTER LUCIUS & BRÜNING, OF HÖCHST-ON-THE-MAIN, GERMANY, A CORPORATION OF GERMANY.

APPARATUS FOR DYEING LOOSE TEXTILE GOODS.

1,071,022.

Specification of Letters Patent.

Patented Aug. 26, 1913.

Application filed February 7, 1912. Serial No. 676,881.

To all whom it may concern:

Be it known that I, WALDEMAR BERGER, engineer, a citizen of the Empire of Germany, residing at Höchst-on-the-Main, Germany, have invented certain new and useful Improvements in Apparatus for Dyeing Loose Textile Goods, of which the following is a specification.

It has been impossible in practice to dye loose textile goods with sulfurized dyestuffs and vat-dye-stuffs in a continuous operation, because thorough and uniform dyeings were unattainable owing to the fact that the material would not sufficiently absorb the dyestuff in passing through the dye-bath. The uneven and incomplete dyeing was due in the first place to the uneven penetration of the dye-liquor into the material, and secondly to the fact that the loose textile goods carry along air which very unfavorably affects the dyeing process, especially when vat-dyestuffs are used.

Now, my present invention relates to an apparatus, by which it is possible to dye loose textile goods in an excellent manner as a continuous operation. This is attained by liberating from the loose textile goods the air entangled in them by subjecting them to pressure when they enter the dye-bath; and by then alternately pressing the textile material while it is in the dye-liquor and allowing it to become loose so that it is again saturated with the liquor. In this manner the fibers are so thoroughly imbued with the liquor that a uniform and complete dyeing is obtained.

Considerable difficulties were encountered in putting this invention into practice, because the loose material while immersed in the dye-bath has a great tendency to ascend and consequently to accumulate at the upper guide rollers when the usual vertical travel is used, whereby a regular and smooth passage through the machine becomes impossible. According to the invention this drawback is obviated by causing the material, which should be placed as loosely as possible, to move in a horizontal direction. However, even this arrangement gave rise to difficulties, owing to the natural tendency of the fibers to ascend, in consequence whereof they accumulate at the guide rollers which reverse the direction of travel. These difficulties can be removed by bring-

ing the conveying bands together (which in order to allow the material to swell are separated a certain distance from each other) at the said rollers, so that they hold the material firmly and convey it uniformly over the rollers.

The present invention is illustrated in the accompanying drawings, in which—

Figure 1 is a vertical longitudinal section of the dye-vat, showing the conveyer bands and the fibers between them, the guide-and squeezing-rolls being shown in end elevation; Fig. 2 is an enlarged detail of a guide-roll, conveyer bands carried by superposed chains, and an interposed block containing small spacing-rollers, on the line II—II of Fig. 4; Fig. 3 is a sectional detail of a pair of squeezing-rolls, the conveyer bands, and two spacing blocks and rollers, on line III—III of Fig. 5; Fig. 4 is a detail view of the parts shown in Fig. 2, viewed at right angles thereto, the wall of the dye-vat in which the guide-roll is journaled being shown in vertical section, and the block carrying the spacing-rollers being shown in section on the line IV—IV, Fig. 2; Fig. 5 is a transverse vertical section on line V—V of Fig. 3; Figs. 6 and 7 are detail views of a modified guide-roll and conveyer bands, the chains carrying the conveyer bands being side by side, Fig. 6 illustrating the roll in vertical axial section, and Fig. 7 being an end view; and Fig. 8 is a transverse vertical section of combined guide- and squeezing-rolls used with the type of conveyer bands shown in Figs. 6 and 7.

As shown in the drawings, the material enters the vat in an integral layer, and is not disintegrated or torn apart during its travel through the vat. On entering the dye-liquor it is squeezed between rolls *e* for the purpose of expressing the air from it.

The continuous conveying bands *a* are made up of slats *b* and carry the material between them. These bands travel on small rollers *c* (Figs. 2, 3 and 4) so placed that as the bands approach the guide rolls *d* they come close together, and having passed the rolls *d*, part company again. The rollers *c* and *d* are attached to the sides (*f*) of the trough. In order to avoid trouble caused by the fibers clogging the bearings of rollers *c*, the latter are mounted in cavities *c'* in blocks *g* suitably attached to the sides (*f*).

of the trough, and the rolls *d* are suitably journaled in casings *f'* which are secured with a liquid-tight joint to the walls *f* of the dye-vat.

5 As shown in Fig. 1, in order that the material may not carry more liquor from the vat than is necessary, it is passed finally between squeezing rolls *h* as it leaves the liquor, but in order to felt the fibers and to 10 effect a preliminary squeezing and also aid in separating loose fibers from conveyer band *a'*, before it enters between these rolls it is pressed while still on the lower band by rolls *i i'*, the construction of the latter of 15 which is similar to that of the squeezing roll *m* presently to be described; the material is thus formed into a felt-like mass which readily leaves the band as the latter turns around the roll *k*, whereas it has 20 heretofore been found very difficult to remove the material from the band when it has not been squeezed by such rolls *i i'*. The slats *b* are attached to brackets *b'*, the latter serving as supports for the pintles of 25 the conveyer-chains *l* and *l'* and are spaced apart sufficiently to allow access of liquor to the material; they must be strong enough to withstand the pressure of the several 30 squeezing rolls. The fact that the slats are spaced apart requires some special arrangement for insuring the application of uniform pressure of the squeezing rolls, as otherwise the dyed material may have a striped appearance.

35 In Figs. 1, 3 and 5, the squeezing rolls *m m'* are provided with teeth which engage in the spaces between the slats and are of the same depth as the slats. The latter are preferably of trapezoidal cross section and 40 the teeth are of corresponding section. Another mode of effecting uniform pressure consists in applying the squeezing rolls at a curve in the conveying band and so mounting the slats on the chains that as they pass 45 around this curve the slats come substantially in contact with each other, as illustrated in Fig. 8. The slats are mounted on the chains so that the said chains are all in the same plane, with the result that at alternate guide 50 rolls *d* the chains are on the inside of the curve, as shown in Figs. 6 and 7, while at the other guide rolls the chains are on the outside of the curve as shown in Fig. 8. In the latter case the slats come substantially 55 in contact with each other as they pass the curve and form approximately continuous surfaces, against which toothless pressure rolls *m²* may be applied.

Having now particularly described my invention, I declare that what I claim is:

1. The herein-described apparatus for dyeing loose material in a continuous operation by alternately squeezing the material and allowing it to become loose in the 65 dye-bath, comprising conveying bands con-

sisting of slats suitably spaced apart, between which bands the material is carried in the dye-bath; guide rolls whereby during the horizontal travel of the bands the latter are so far separated from each other that the material is loose, while at the guide rolls which reverse the direction of travel the bands approach each other and hold the material tightly; and squeezing rolls at one or more points of the conveying bands which 70 press the latter together, substantially as described.

2. In an apparatus for dyeing loose textile materials, squeezing rolls having teeth corresponding in cross section with the cross 80 section of the spaces between the slats, so that the teeth engage in these spaces and the material is uniformly pressed, substantially as described.

3. An apparatus for dyeing loose materials, comprising a vat, means for conveying an integral layer of the material through the vat, and means for repeatedly compressing and decreasing the pressure on said 85 layer as it travels through the vat.

4. In an apparatus for dyeing loose materials, a vat, means for conveying an integral layer of the material through the vat, comprising two adjacent traveling bands each consisting of a pair of chains and slats 95 attached thereto, and means for repeatedly decreasing and increasing the distance between the bands.

5. In an apparatus for dyeing loose textile materials, traveling conveying bands, 100 comprising two pairs of chains with slats attached to each pair of said chains, separating blocks for increasing the distance between the bands, said blocks having pointed ends, cavities in said blocks, and rollers in 105 said cavities.

6. In an apparatus for dyeing loose textile materials, traveling conveying bands comprising pairs of chains with slats attached to each pair of said chains, separating blocks for increasing the distance between the bands, said blocks having pointed ends, and compressing means between the 110 ends of adjacent blocks.

7. In an apparatus for dyeing loose textile materials, traveling conveying bands comprising pairs of chains, and trapezoidal-shaped spaced slats attached to said pairs of chains, the wider faces of the slats on one band confronting the wider faces of the 115 slats on the other band, and means co-operating with said bands to alternately loosen and compress said materials while in said dye-vat.

8. In an apparatus for dyeing loose textile materials, traveling conveying bands comprising pairs of chains, trapezoidal-shaped spaced slats attached by their narrower faces to said pairs of chains, and co-operating toothed wheels adapted to fit in 120 125 130

the spaces between said slats and form a substantially uniform surface with the wider faces of the slats.

9. An apparatus for dyeing loose textile materials, comprising a dye-vat, confronting traveling conveying bands within said dye-vat, said confronting bands consisting of spaced slats mounted upon chains the pintles of which are in the same plane, and 5 rolls mounted in said dye-vat and serving to support said conveying bands so that as the bands bend around successive rolls the spaces between the slats are alternately opened and closed, thereby forming alternately discontinuous and continuous conveying surfaces.

10. In an apparatus for dyeing loose textile materials, traveling conveying bands comprising two pairs of chains, spaced slats 20 attached to said chains, said slats forming a surface for conveying the textile materials, a toothed roll below one of the bands and having its teeth arranged to mesh in the spaces between the slats, and a roll above 25 the band, said rolls adapted to compress and separate said textile materials from the slats.

11. In an apparatus for dyeing loose textile materials, traveling conveying bands comprising two pairs of chains, spaced slats 30 attached to each pair of said chains, blocks having sloping pointed ends between the bands for gradually separating said bands, and toothed compressing rolls on the outer

sides of the conveying bands, having their 35 teeth arranged to mesh in the spaces between the slats and to decrease the distance between the bands at a point between the ends of adjacent separating blocks.

12. In an apparatus for dyeing loose 40 textile materials, adjacent traveling conveying bands comprising two pairs of chains and slats attached thereto, portions of said bands being superposed, means to supply materials to be dyed between the bands, and 45 means to alternately loosen and compress the material to be dyed while between the bands.

13. An apparatus for dyeing loose textile materials, comprising a dye-vat adapted to 50 contain a dye-liquor, traveling conveying bands within said vat comprising two pairs of chains and slats attached thereto, means to supply materials to be dyed between said bands, means to alternately loosen and 55 compress the material to be dyed while between the bands, means to separate the material from said bands and to compress the material thereby removing dye-liquor, and means to remove the remaining dye-liquor 60 from said material.

In testimony whereof, I affix my signature in presence of two witnesses.
